United States Patent

Des. 235,296
Patented June 10, 1975

235,296

BAKERS RACK OR SIMILAR ARTICLE

Jonathan Ginat, New York, N.Y. (% A.C.I. Industries, Inc., 38-60 Review Ave., Long Island City, N.Y. 11100)

Filed Oct. 16, 1973, Ser. No. 406,823

Term of patent 14 years

Int. Cl. D6—04

U.S. Cl. D6—186

FIG. 1

FIG. 1 is a perspective view of a bakers rack or similar article showing my new design.

FIG. 2 is a side elevational view of the bakers rack or similar article shown in FIG. 1, the far side being a mirror image of the near side.

I claim:

The ornamental design for a bakers rack or similar article, as shown and described.

FIG. 2
